UNITED STATES PATENT OFFICE.

ROBERT ANDERSON AND GEORGE ANDERSON, OF EDINBURGH, SCOTLAND.

DESIGN FOR A FOOT-CYCLE FRAME.

SPECIFICATION forming part of Design No. 25,998, dated September 8, 1896.

Application filed June 12, 1896. Serial No. 595,362. Term of patent 14 years.

To all whom it may concern:

Be it known that we, ROBERT ANDERSON, manufacturer of sports' appliances, and GEORGE ANDERSON, civil engineer, subjects 5 of the Queen of the United Kingdom of Great Britain and Ireland, residing at 67 Princes Street, Edinburgh, in the county of Mid-Lothian, North Britain, have invented and produced a new and original Design for Foot-10 Cycle Frames, of which the following is a specification, reference being had to the accompanying drawings, in which—

Figure 1 is an elevation, Fig. 2 a plan, and Fig. 3 a cross-section, of our frame. 15 The essential feature of our design is the frame of rail-shape or T-shape cross-section. Referring to the drawings, A is a blade of rail-shape or T-shape cross-section, as shown in Fig. 3, having the forked end portions B 20 B' and the inclined front or toe portion C,

and the rear or heel portion D. The arrangement of the frame is such that the toe portion C and heel portion D are below the level of the journal ends of the forks B and B'. The heel portion D is formed with curved 25 flanges d, to which the leather-gaiter portion (not shown) is secured at e.

f are holes to which the ankle-strap may be riveted, and g are holes to which the toe-straps may be riveted. The toe and heel platforms 30 are formed by simply widening out portions of the top of the T or rail shape frame-section.

We claim—

The design for foot-cycle frames substantially as herein shown and described.

ROBT. ANDERSON.
GEO. ANDERSON.
